UNITED STATES PATENT OFFICE.

JOHN WILLIAM JACOBS, OF NEW YORK, N. Y., ASSIGNOR OF ONE-THIRD TO HILDA HOFFMANN, OF FAR ROCKAWAY, NEW YORK.

RETAINER FOR HAT-PROTECTORS.

1,171,204.

Specification of Letters Patent. Patented Feb. 8, 1916.

Application filed September 9, 1915. Serial No. 49,724.

To all whom it may concern:

Be it known that I, JOHN W. JACOBS, a citizen of the United States, and a resident of the city of New York, Far Rockaway, 5 borough of Queens, in the county of Queens and State of New York, have invented a new and Improved Retainer for Hat-Protectors, of which the following is a full, clear, and exact description.

- 10 This invention relates to wearing apparel and has particular reference to retainers for protectors for dress hats especially for men's wear, although the invention is not to be so limited in its adaptation. 15 The main object of the invention is to improve the means for temporarily holding or supporting the protector within the crown of the hat in such a manner as to be readily and quickly removed for application 20 when required in the case of a sudden shower, for instance.

With the foregoing and other objects in view, the invention consists in the arrangement and combination of parts hereinafter 25 described and claimed, and while the invention is not restricted to the exact details of construction disclosed herein, still for the purpose of illustrating a practical embodiment thereof reference is had to the accompanying drawings, in which like reference 30 characters designate the same parts in the several views, and in which—

Figure 1 is a diagrammatic representation of a conventional form of hat with the protector covering applied thereto; Fig. 2 is a similar view showing an inside view of the hat; Fig. 3 is a vertical longitudinal section of a common type of sailor hat, full lines indicating the protector in folded position 40 within the crown and held therein by the improved retainer, dotted lines indicating the probable position of the protector in operative condition; Fig. 4 is a bottom plan view of the protector detached from the hat, the view being practically on the same scale as that of Fig. 3; and Fig. 5 is a perspective view of the retaining device coöperating with the inner wall of the hat crown.

By way of an illustration of a practical embodiment of the improvement, I show a hat comprising a crown 10 and brim 11 having a sweat band 12 and outer band 13. As a means for protecting the crown and brim from damaging conditions such as rain, dust, mud, or the like, I provide a protector 55

covering 14 made preferably of a good quality of light sheet rubber or its equivalent and preferably of a light color or a color simulating somewhat the color of the hat so as to be comparatively inconspicuous when in use, such protector being formed with a beaded periphery 14' adapted to be engaged over the periphery of the brim 11, as shown in the first three figures. In this condition the protector thoroughly covers the 60 crown and forms a sloping water shed to direct the rain or the like therefrom well downwardly over the brim. When not in use, the protector is adapted to be folded or otherwise disposed in a small compass and placed within the top of the crown, as shown in Fig. 3, between the top of the crown and the lining of the hat. The usual hat lining may easily be removed for this purpose and replaced by a special lining shown at 15, 70 or, if preferred, the same lining may be returned to its place after the retaining device is introduced.

The retaining device comprises a spider-like combination of flexible elastic spring 80 arms 16 shown as two in number, crossing each other at the center at right angles and having their extreme ends directed outwardly slightly, as indicated at 16', whereby they serve to tend to engage the inner surface of the hat crown with a moderate degree of force. In other words, after the protector 14 in its folded position is dropped into place in the top of the crown, as the hat is lying upside down upon a table for 90 instance, the retaining device is dropped squarely within the crown and forced directly downwardly at the center, causing the prongs 16' to be bent toward one another, the portions of the arms adjacent the prongs 95 being bent in this operation in close parallelism with the vertical wall of the crown. The prongs 16', therefore, upon digging into the body of the crown above or beneath the sweat band 12 will hold the retaining device 100 steadily in position and thereby hold the protector as indicated in Fig. 3.

At 17 I show a flat plate of any suitable form and outline and made of a good quality of cardboard or the like, which is secured 105 to the retainer at the center of the crown and which serves to assist the operator in forcing the retainer into retaining position and to hold the protector well seated in its substantially flat condition.

At 18 I form a wire hoop carried between the plies 19 and 20 constituting the top portion of the lining 15, all of the lining parts adapted to be secured by overwhipping, or ⁵ the like, to the arms 16. This hoop 18 is of substantially the same outline as the crown of the hat and may be of a size to adapt the retaining device to any standard size of hat crown. Among its functions is to stiffen ¹⁰ the top portion of the lining so as to make the same lie in a substantially flat condition when in retaining position.

I claim:

The herein described retainer for hat pro-

tectors, the same comprising a plurality of ¹⁵ spring arms connected to one another and terminating in prongs adapted to engage directly against the inner surface of the hat crown, a crown lining connected to the spring members, and a wire hoop carried ²⁰ by the lining in a plane closely parallel to the general plane of the spring members, substantially as and for the purposes set forth.

JOHN WILLIAM JACOBS. [L. S.]
